UNITED STATES PATENT OFFICE.

WILLIAM J. DECKER, OF DETROIT, MICHIGAN.

CURTAIN-WINDOW.

1,347,499.

Specification of Letters Patent.

Patented July 27, 1920.

Application filed July 8, 1918. Serial No. 243,761.

To all whom it may concern:

Be it known that I, WILLIAM J. DECKER, a citizen of the United States, and residing at Detroit, in the county of Wayne and State of Michigan, have invented a new and Improved Curtain-Window, of which the following is a specification.

The invention has reference to means for mounting a glass in a curtain or other fabric element such, for example, as the collapsible top structure of an automobile. It provides a mounting which is concealed from within by the single fabric whereby it is carried.

It further provides a mounting which is relatively inexpensive both as concerns material used and manipulative operations involved in its manufacture and assembly.

The invention further consists in a mounting wherein the supporting fabric enters the glass holding frame from the inner edge of the glass opening and is thereafter drawn out taut along the face of the frame to effectually conceal the latter. All projecting and unsightly tongues and the like are thus avoided, and the fabric is made to appear to merge into the glass itself.

Again, the invention consists in a two part glass supporting frame the inner element of which is received in the outer and overlapped throughout by a fabric sheet the edge portion of which is wholly concealed from the outside by the frame and the body portion of which, in turn, conceals the frame from the inside.

The invention is also concerned with certain tongues or the equivalent whereby the panel is properly centered and whereby the invention is rendered especially applicable to glass panels having bevel edges.

It further consists in certain details of construction shown, described and particularly pointed out in the claims.

In the drawings, Figure 1 is an outside elevation showing one embodiment of my invention. Fig. 2 is a plan view looking at the outside confining member from the side opposite that which appears in Fig. 1, and showing the tongues before they are bent over between the inner confining member and the fabric. Fig. 3 is a section on the line 3—3 of Fig. 2. Fig. 4 is a plan view showing the inner confining member before the tongues are clenched on the fabric. Fig. 5 is a section on the line 5—5 of Fig. 1, and Fig. 6 is a similar enlarged fragmentary section of a slightly modified structure. Fig.

7 is a view, similar to Fig. 6, showing the parts detached from one another. Figs. 8 and 9 are views, similar to Fig. 6, showing modifications. Fig. 10 is a fragmentary plan view of the inner member which appears in Fig. 8. Fig. 11 is a view, similar to Fig. 2, and showing centering tongues or elements whereby the mounting is rendered especially suitable for glass having beveled edges.

1 indicates the curtain or top material or other fabric wherein the glass panel 2 of any desired shape is to be supported. It will be observed that the fabric is a single unlined sheet although it might be in the form of two or more sheets conforming closely to each other throughout and in one sense forming a single sheet. This sheet or sheets is cut away to form an opening of proper shape and size and is slipped through a thin plate 3, preferably metal, of similar configuration as indicated in Fig. 7. Formed on the plate in any suitable way are the tongues 4 (Fig. 4) or 5 (Fig. 10) or other gripping means, which are preferably passed through the edge portion of the fabric, and bent over if necessary, as shown in Figs. 6 and 8 to hold the latter firmly. The fabric thus presents a relatively soft face against which the inner surface 6 of the glass may bear. Coöoperating with the parts thus far described is an outer member 8 of stamped metal the cross section of which is preferably curved as shown. This member preferably extends unbroken around the entire opening, as does the member 3, and its inner edge 9 preferably bears directly on the outer face of the glass, whereas its other or outer edge has formed thereon a series of tongues 95

10, or other mechanically equivalent parts or part, that preferably stand, before assembly, in a plane substantially perpendicular to the general plane of the member, (Fig. 2) and are thereafter bent inwardly along 100 the inner face of the part 3, say by a suitable tool, as shown in Figs. 6 and 9. The outer edge is preferably curled over between the tongues, as shown at 11 in Fig. 3, to avoid a sharp edge. When the fabric is then 105 drawn taut it actually or practically conceals the entire frame or mounting from view from the inside of the car and presents to the eye simply a glass panel surrounded by and substantially continuous 110 with the top or curtain fabric. It will be understood that the arrangement may be

reversed if desired, that is, the frame element 8 may be arranged on the inside, thus presenting merely the fabric and the glass to view from the outside of the car.

- 5 Now referring more particularly to Figs. 9 to 11:—The panel 2 in this instance has outer bevel edges, and the outer frame element 12, which corresponds to the element 8 is provided on its inner edge with a plurality of reentrant centering tongues or the like 13, the inner portions 14 of which are bent over against the inner surface of the glass. Besides a considerable saving in the amount of glass required, the bevel is thus 10 properly and uniformly presented. This centering feature is, of course, applicable with flat non-beveled panels, and adds no appreciable expense, since the inner metal is otherwise wasted in the dies.
- 15 20 In the modification shown in Fig. 8, the tongues 10 are superseded by a rib 15, that may be continuous, and the element 3 is, in this case, formed of spring metal and severed as indicated in dotted lines at 16, Fig. 4; 25 the resilient member is then inserted into the outer member and allowed to expand to final position in the latter in an obvious manner.

Various changes other than those suggested, may be made in the details of construction without departing from the spirit of the invention. I do not, therefore, wish to be limited except as indicated by the subjoined claims.

35 I claim:—

1. In combination, a fabric sheet having an opening and being turned back on itself around the opening, a frame member positioned between the turned back portion and 40 the main portion of the sheet, a glass panel, and a second frame member engaging the glass panel and extending around the first frame member and inwardly between it and the main portion of the sheet, the curtain being 45 imperforate around said opening and one side of the curtain being smooth and unbroken, all of the frame and the glass being on the other side of the curtain.

2. In combination, a frame member and 50 a fabric sheet having an opening and being turned back on itself over said frame mem-

ber, a glass panel closing said opening, and a second frame member engaging the glass panel with its inner edge and having its outer edge extending around the first frame member and provided with a series of in-turned tongues extending inwardly between the first frame member and the main portion of the fabric sheet, the curtain being imperforate around said opening and one side of the curtain being smooth and unbroken, all of the frame and the glass being on the other side of the curtain.

3. In combination, a fabric sheet having an opening therein and being turned back upon itself around the opening, a metal member interposed between the turned back portion and the rest of the sheet and gripping said turned back portion, a glass panel, a second metal member extending around the edge of the panel and in between the first metal member and the main portion of the sheet and partially inclosing the turned back edge of the sheet and the edge of the first metal member to hold said metal members together, 75 whereby the marginal edge of the glass and the first mentioned metal member, together with the turned back edge of the sheet, are concealed from view from one side by the second metal member, and whereby the first 80 metal member and the interposed portion of the second metal member are concealed from view from the opposite side by the main portion of the sheet.

4. In combination, a fabric sheet having 85 an opening and being turned back on itself around the opening, a frame member positioned between the turned back portion and the main portion of the sheet and provided with gripping means for securing it to said 90 turned back portion of the sheet, a glass panel, and a second frame member engaging the glass panel and extending around the outer edge of the first frame member and inwardly between said outer edge and the 95 main portion of the sheet, the curtain being imperforate around said opening and one side of the curtain being smooth and unbroken, all of the frame and the glass being on the other side of the curtain.

WILLIAM J. DECKER.
